READILY ADJUSTABLE FLEXIBLE HOLDER

Roger William McBrien, East Alton, Ill.

Application February 23, 1955, Serial No. 489,926

5 Claims. (Cl. 24—243)

The invention relates to holders of the type comprising a rigid main member and a flexible band forming a loop projecting from the main member and adjustable for securely surrounding the article to be held. The invention is of the general type shown in Patent No. 2,693,015 and is particularly adapted for holding tubes or flasks in chemical laboratories.

One object of the invention is to more readily adjust the length of the flexible band projecting from the rigid member to accommodate different sizes of flasks or other articles to be held.

Another object is to arrange a holder of this type so that the article being held may be readily released from the holder.

Another object is to accommodate a greater supply of flexible band within a main member but without increasing the diameter of the member.

Another object is to simplify the jaw structure with a holder.

In the accompanying drawings illustrating selected embodiments of the invention:

Figure 1 shows a stand with the holder mounted on it and supporting a flask above the bottom of the stand.

Figure 2 is an elongated horizontal section through the holder shown in Figure 1 and is drawn to an enlarged scale.

Figure 3 is a detail view of parts shown in Figure 2 but moved to a different relative position and is drawn to a still larger scale.

Figure 4 is a vertical section through the jaw and rigid handle portion of the holder illustrating another form of the invention.

Figure 5 is a top view of the rigid handle portion of the holder shown in Figure 4.

Figure 6 is a detail of the band clamp shown in Figure 4.

Figure 7 is a view of the device shown in Figure 6 looking at an angle of 90°.

The holder comprises a rigid tubular handle 1 and a flexible band 2 of stainless steel projecting from the holder and clamping means associated with the handle for gripping the band at a selected point in its length to hold the band tightly around an object, such as the neck of the flask F. The tube 1 may be held in the hand and inserted in the block B slideably vertically on the upright U of a stand S. The left hand end of handle 1 is secured to an upright plate 3 carrying at each of its upper and lower ends a pair of fingers 4 forming a seat for the flask neck. A latch 9 is secured to one end of band 2 by inserting the end of the band through slots in the latch and punching a hole in the end of the band for a screw 5 threaded into the latch. The latch terminates in a hook 6 which may be inserted through an opening 7 in plate 3 at one side of the latter and between the corresponding upper and lower fingers 4. The opposite end 8 of the latch forms a guide for the adjacent portion of the band and a convenient element for engagement by the finger or thumb of the user.

The other end of band 2 is passed between opposing faces of a clamp structure which includes a U-shaped stirrup 10 secured by a rivet or screw 11 to a bar 12 having threads at opposite sides mounting a nut 13. A second U-shaped stirrup 14 has its cross bar received between the legs of stirrup 10 and has its legs slideable along opposite sides of bar 12. A follower 15 is positioned between nut 13 and the end of stirrup 14 and

2

forms a substantial bearing for the nut. Flexible band 2 is doubled one or more times and passed freely through the space between the cross bars of U stirrups 10 and 14 (see Figure 2) and when the length of the band projecting from the tube handle has been determined roughly, nut 13 is advanced to the left along bar 12 to clamp the band between the cross bars of the two stirrups.

Bar 12 and associated band clamping parts and a considerable portion of the doubled band are then inserted in tube 1, the bar being passed through a square hole in a collar 16 rigid with the tube and thereby held against rotation in the tube. The user threads an elongated nut 18 onto the end of bar 12. Preferably a short coil spring 17 surrounds bar 12 at the right of collar 16 and is contacted by the forward movement of nut 18 which draws the band further into the tube until the object surrounded by the band is gripped as tightly as is necessary to hold it against slipping, as may be determined by the compression of spring 17. Preferably sufficient tension will be placed on the band before the spring is solid. An inturned lip 1a at the right hand end of the tube is received in a peripheral groove in the nut and retains the nut against removal.

With this arrangement, the flask may be readily removed from the holder by merely loosening the tension of nut 18 and tilting latch 9 until its hook 6 will slide through opening 7. When the flask or another object is to be again held by the looped band, the latter is placed around the article and hooks 6 inserted through openings 7 and the opposite end of the band drawn into the tube by bar 12 and nut 18.

If a substantially larger or smaller object is to be secured to the holder, nut 18 is removed from the end of the bar and the bar drawn out of the opposite end of the tube. Clamping nut 13 is unscrewed a few turns to relieve the pressure on the band exerted by stirrups 10 and 14 and the band is shifted through the space between stirrups 10 and 14 until as much of the band as is estimated necessary for the different sized object is available. Nut 13 is then tightened again, the bar and clamp and associated length of band is again inserted into tube 1 until nut 18 can be threaded onto the end of bar 12.

Figures 4-7 show another arrangement in which tube 21 is much shorter than tube 1 and bar 22 is substantially equal in length to tube 21. Nut 28 applied to bar 22 is of cup section and receives coil spring 27, which is seated against the outer end of tube 21. Nut 28 has internal threads fitting over external threads on the tubular handle 21.

A simpler form of clamp for the band is embodied in this structure and is detailed in Figures 6 and 7 in that a single U-shaped member or stirrup 24 is pivoted at 25 on bar 22 and the cross bar of stirrup 24 forms a yielding element permitting the swinging of the stirrup between the two positions shown in Figure 7. When the stirrup and bar are in alignment, there will be sufficient friction to securely hold band 20. One or both legs of stirrup 24 may be dimpled at 26 to be received in corresponding depressions 27 in the bar to more readily hold stirrup and bar aligned.

In this form of the invention, the tubular handle may be split at one end and the split ends spaced apart as shown in Figure 5 to form the object seat on the handle and also form concavo-convex guides for the band.

With this arrangement, both end portions of the loop formed by the band are drawn into the tube simultaneously when nut 28 is rotated, thus making a more rapid tightening action than when only one end of the band is being drawn into the tube. However, it may be necessary to release a greater portion of the doubled band

length to provide sufficient slack to remove the article being held.

With both forms of the holder, the object being held may expand or contract without loosening the grip of the holder and an inexperienced operator may hold even a fragile article more readily than if the grip is dependent upon an exact adjustment of the clamping screw. This feature is particularly advantageous if the article being held is in a vibration area where insufficient tightening would cause the object to slip downwardly or where excess tightening would cause the article to break. With the arrangement first described, the tightening nut cannot be misplaced because it will be retained in assembly with the tube by lip 1a. The clamping of the band at any point in its length and the housing of a substantial length of surplus band in the tube makes it possible to obtain accurate adjustment of the band for different sizes of objects. The shape of latch 9 with its hook 6 facilitates the ready release of the object from the band without the necessity of extensive unscrewing of the tightening nut 18.

Variations in the details of the structure may be made while retaining all of the advantages mentioned and without departing from the spirit of the invention and the exclusive use of those modifications coming within the scope of the claims is contemplated.

What is claimed is:

1. An adjustable holder of the kind described comprising an elongated open end sleeve, a bar slidable in said sleeve and normally retained therein with one end spaced inwardly from the ends of the sleeve, a flexible band having a quick-release hook and eye connection at one end to one end of said sleeve end and forming a loop outwardly of said sleeve end and having a substantial length extending from the loop and secured to said bar and doubled back and forth within said sleeve between the end of the bar and said sleeve end, said sleeve having an interior shoulder facing away from said sleeve end, and a nut partly within the sleeve and rotatably seated on said shoulder and threaded onto said bar and projecting from the opposite end of said sleeve for manual rotation, said sleeve and nut having cooperating circumferential groove and ridge elements retaining the nut assembled with the sleeve.

2. In a holder of the kind described, an open end sleeve, a bar slidable axially therein, a U-shaped stirrup with legs embracing one end of said bar and pivoted thereto and having squared ends, the end piece of the stirrup being movable about its pivot from one side of the bar to the other and into alignment with the bar axis, said end piece being spaced outwardly from the end of the bar when aligned with said axis, a flexible band forming a loop exteriorly of the sleeve and extending into the sleeve and through said stirrup between the end of said bar and the end piece of the stirrup, a follower slidable along the bar toward and from the squared ends of the stirrup, a nut threaded on the bar, to force the follower against the stirrup ends, and a nut threaded onto the bar and seated against the sleeve for moving the bar, stirrup, follower and follower nut as a unit lengthwise through the sleeve.

3. An adjustable holder of the kind described comprising an elongated tubular open ended handle, an elongated bar slidable axially in said handle but held against rotation therein and threaded substantially throughout its length, a flexible band including a loop projecting from one end of said handle and having one end secured to said handle, a manually releasable device mounted on the end of the bar and movable therewith into the handle and frictionally securing the other end of said loop directly to the end of said bar nearer said loop, said band extending from said device toward said handle end and being doubled back and forth within the tubular handle for storage between the end of the bar and said handle end, said handle having a shoulder facing away

from said loop, and a nut threaded onto said bar and seated against said shoulder and projecting from the other end of said handle for manual rotation to draw said bar and doubled band inwardly of the handle.

4. In a holder of the kind described, an open end sleeve, a bar slidable axially therein and through one open end thereof, means holding the bar against rotation following its insertion into the sleeve, a U-shaped stirrup having a cross piece and having legs embracing one end of said bar, there being a pin extending transversely through the bar and the ends of the stirrup legs remote from said cross piece to pivot the stirrup on the bar for swinging movement from a position in which said cross piece is aligned with the bar end, but spaced slightly therefrom to a position at one side of the bar, said stirrup being slidable with said bar in said sleeve when its cross piece is in the first-mentioned position, a flexible band forming a loop exteriorly of one end of the sleeve with end portions passing between the stirrup end piece and the bar end, the stirrup cross piece yielding lengthwise of the stirrup to frictionally grip the band against the bar end when the stirrup cross piece and bar end are directly opposed, the band being readily withdrawn from between the stirrup cross piece and the bar end when the stirrup is moved to the second-mentioned position, and a nut threaded onto the other end of the bar and seated against a shoulder near the other end of the sleeve and rotatable on its seat for moving the bar, stirrup and band as a unit lengthwise of and inwardly of the sleeve.

5. In a holder of the class described, an elongated open end sleeve, a bar slidable lengthwise in and through an open end of the latter, a U-shaped stirrup embracing one end of said bar and comprising parallel legs and a cross piece, there being a pin extending transversely through the bar and the end portions of the stirrup legs to pivot the latter on the bar for swinging the cross piece of the stirrup from a normal position in alignment with the bar to the side of the bar, when the bar is withdrawn from the sleeve, the cross piece of the stirrup being slightly spaced from the end of the bar when the stirrup and bar are aligned, a flexible band forming a loop exteriorly of the sleeve with extended portions spaced from the loop and passing between the stirrup cross piece and the bar end, the stirrup cross piece frictionally engaging and gripping the band against the bar end when the stirrup and the bar are aligned but clearing the band from contact and gripping engagement with the bar when the stirrup cross piece is swung to one side of the bar, and means for moving the bar, stirrup and band as a unit lengthwise in the sleeve to shorten the length of the loop exteriorly of the sleeve.
